HEAT EXCHANGER

Max H. Kuhner, Worcester, Mass., assignor to
 Riley Stoker Corporation, Worcester, Mass., a
 corporation of Massachusetts

Application January 27, 1936, Serial No. 60,922

7 Claims. (Cl. 257—224)

This invention relates to heat exchangers, and more particularly to apparatus of the type having a bank of closely spaced parallel tubes through which a fluid is passed in heat transfer relation to a second fluid outside of the tubes.

Heat exchangers of this type are frequently used to preheat the air for combustion in boiler furnaces, the air ordinarily traveling through the spaces between the tubes, and the flue gases from the boiler traveling through the interior of the tubes in counterflow relation to the air. In such an air preheater it is important to avoid too great a cooling of the flue gases. Most fuels contain water, which is vaporized in the furnace. Additional water vapor is formed by the combustion of the hydrogen in the fuel. This water vapor of course escapes from the boiler with the flue gases, and if the temperature of these gases is lowered too much, water will condense and cause corrosion of the tubes, usually near their discharge ends. Such corrosion may occur in certain of the tubes even though the temperature of the gases leaving the heater is apparently above the danger point. Applicant has discovered that this is caused by cooling the gases more in certain tubes than in others, usually because of non-uniform distribution of the air throughout the spaces between the tubes.

It is accordingly one object of the invention to provide a heat exchanger which will effect a substantially uniform transfer of heat from one fluid to another.

It is a further object of the invention to provide a heat exchanger of the tubular type which is so constructed and arranged as to distribute one of the fluids with substantial uniformity throughout the spaces between the tubes.

It is a further object of the invention to provide a heat exchanger of the tubular type which will be simple and inexpensive to manufacture, and efficient in operation.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts, Fig. 1 is a sectional elevation of a heat exchanger, the lower portion being shown in section on the line 1—1 of Fig. 2, and the upper portion being shown in section on the line 1a—1a of Fig. 2;

Fig. 2 is a section on the line 2—2 of Fig. 1;

Fig. 3 is an enlarged section on the line 3—3 of Fig. 1;

Fig. 4 is an enlarged section on the line 4—4 of Fig. 1; and

Fig. 5 is a fragmentary perspective view of a detail of the construction.

The embodiment illustrated comprises a series of vertical tubes 10 arranged in a rectangular formation and with their ends expanded into upper and lower horizontal tube sheets 11 and 12 respectively. A hood 14 is secured to the upper tube sheet 11 to form a passage 15 with which all the tubes connect at their upper ends. The tubes are divided into two groups by a vertical partition 16 which extends upwardly from the lower tube sheet 12 and terminates somewhat below the upper tube sheet 11. This partition 16 is supported at the top by tie rods 18 extending downwardly from a horizontal I-beam 19 mounted above the upper tube sheet. A gas inlet duct 20 connects with the lower ends of the tubes at one side of the partition, and a gas outlet duct 21 connects with the lower ends of the tubes at the other side of the partition. The gas is delivered by the duct 20 and flows upwardly through the corresponding tubes to the passage 15 and thence downwardly through the remaining tubes to the outlet duct 21.

A second fluid, such as air, is caused to flow in contact with the outer surfaces of the tubes and in counterflow relation with the gas. For this purpose the intermediate portions of the tubes are enclosed on all four sides by casing walls 23.

The upper edges of the walls 23 are spaced below the upper tube sheet 11, and the lower edges of these walls are spaced above the lower tube sheet 12. A casing 24 connects the walls 23 with the upper tube sheet 11 and forms a passage 25 which surrounds the upper portions of the tubes 10 on all four sides.

An air inlet duct or passage 26 is provided to deliver air to the lower portions of the tubes adjacent to the gas outlet 21, and an air outlet duct or passage 27 is provided to receive air from the lower portions of the tubes adjacent to the gas inlet 20. As shown in Fig. 2, the ducts 26 and 27 jointly surround the tubes on all four sides.

The air is delivered by the duct 26 and flows beneath the lower edge of the casing 23 into the spaces between the tubes and thence upwardly in contact with the outer surfaces of the tubes. Some of the air then flows over the upper edge of the partition 16, and the remainder flows into the passage 25 and travels through this passage and into the spaces between the tubes at the other side of the partition. The

air then flows downwardly in contact with the outer surfaces of these tubes, and escapes at the bottom into the duct 27.

The tubes 10 are preferably closely spaced, to provide a comparatively large heating surface in the space available. In the preferred construction illustrated the tubes are arranged in echelon formation, and in general each tube is equidistant from six surrounding tubes. Certain rows of tubes extend parallel to the partition 16, whereas other rows extend in diverging directions at angles of sixty degrees to the partition.

It is important to obtain substantially uniform distribution of the air among the tubes. For this purpose the tubes are divided into groups which are separated by lanes 29 (Fig. 2) extending at right angles to the partition 16. The width of these lanes as shown is approximately equal to the diameter of the tubes. In the embodiment illustrated, lanes 29 divide the tubes into three groups at each side of the partition. In each of these groups there is provided a pair of converging lanes 30 which extend inwardly from the outer margin of the group, opposite the partition 16, at angles of sixty degrees to the partition. These lanes may be formed by omitting tubes from certain of the diagonal rows. The lanes 29 and 30 form paths of decreased resistance which facilitate the flow of air into and out of the spaces between the tubes.

With the construction as so far described, the air could flow laterally into the lanes 29 and 30, and then along these lanes in directions parallel to the tubes. This would decrease the efficiency of the heat transfer by allowing a considerable portion of the air to escape intimate contact with the tubes. In order to prevent this, I provide suitable baffles in the lanes. In the embodiment illustrated, I have shown a plurality of vertically spaced horizontal angle members 32 mounted in each lane 29, and a plurality of vertically spaced horizontal angle members 33 mounted in each lane 30. As shown particularly in Figs. 3 and 4, the angle members are arranged with their concave faces upward on the side of the partition 16 where the air is flowing upwardly, and with their concave faces downward on the other side of the partition. The angle members 32 are supported at their ends by the casing 23 and by the partition 16. The angle members 33 are supported at one end by the casing 23 and at the other end by T-shaped columns 34 located at the intersection of each pair of lanes 30. Horizontal angle members 40 are secured to the opposite sides of the partition 16 to stiffen the same and to deflect the air away from the partition and into contact with the tubes.

The operation of the invention will now be apparent from the above disclosure. Hot flue gases are delivered to the inlet duct 20 and flow upwardly through the corresponding tubes 10 to the passage 15 and thence downwardly through the tubes on the other side of the partition 16 to the outlet duct 21. Cold air is delivered to the inlet duct 26 and flows laterally beneath the lower edge of the casing 23 and into the spaces between the tubes. Some of this air flows laterally through the lanes 29 and 30, and thus is able to reach the tubes near the partition 16, which are relatively remote from the air duct 26. In this manner a comparatively uniform distribution of the air is obtained among the lower portions of the tubes. This air now flows upwardly in contact with the tubes, and as it approaches the upper tube sheet 11 a portion of the air flows over the

top of the partition 16 while the remainder flows laterally into the passage 25 and thus around into contact with the tubes on the other side of the partition. The air thereupon flows downwardly along the tubes, and as it approaches the lower edge of the casing 23 and into the outlet duct 27. The lanes 29 and 30 facilitate the entrance of the air into the spaces between the tubes and the exit of the air from these spaces. The baffles 32 and 33 prevent the air from traveling along these lanes in vertical directions. Heat is transferred through the walls of the tubes 10 from the flue gases inside the tubes to the air outside the tubes, and since both fluids are substantially uniformly distributed with relation to the tubes the temperature of the gas leaving the various tubes is likewise uniform. It is therefore possible to reduce the gas temperature to a comparatively low value without encountering abnormally low temperatures and resultant condensation and corrosion in certain of the tubes. The apparatus is simple and inexpensive to manufacture and efficient in operation.

Having thus described my invention, what I claim as new and desire to secure by Letters Patent is:

1. A heat exchanger comprising a pair of spaced tube sheets, a group of tubes connecting said sheets, means to pass a fluid through the interior of the tubes, an inlet passage located adjacent to one of the tube sheets and arranged to deliver a second fluid to the spaces between the tubes, the tubes being for the most part closely spaced but arranged to provide lanes of substantial width which communicate with the inlet passage and through which the second fluid may flow transversely of the tubes, walls enclosing the tubes and providing a passage through which the second fluid may flow longitudinally of the tubes, and baffles located in said lanes to prevent flow along the lanes and longitudinally of the tubes.

2. A heat exchanger comprising a pair of spaced tube sheets, a group of tubes connecting said sheets, means to pass a fluid through the interior of the tubes, an inlet passage located adjacent to one of the tube sheets and arranged to deliver a second fluid to the spaces between the tubes, the tubes being for the most part closely spaced but arranged to provide lanes of substantial width which communicate with the inlet passage and through which the second fluid may flow transversely of the tubes, walls enclosing the tubes and providing a passage through which the second fluid may flow longitudinally of the tubes, and a series of baffles located in each lane and spaced apart longitudinally of the tubes, said baffles preventing the second fluid from flowing along the lanes and longitudinally of the tubes.

3. A heat exchanger comprising a pair of spaced tube sheets, a group of tubes connecting said sheets and arranged in a plurality of rows in echelon formation, means to pass a fluid through the interior of the tubes, an inlet passage located adjacent to one of the tube sheets and arranged to deliver a second fluid to the spaces between the tubes, tubes being omitted in certain rows to provide lanes of substantial width which communicate with the inlet passage and through which the second fluid may flow transversely of the tubes, walls enclosing the tubes and providing a passage through which the second fluid may flow longitudinally of the tubes, and baffles located in said lanes to prevent flow along the lanes and longitudinally of the tubes.

4. A heat exchanger comprising a pair of spaced tube sheets, a group of tubes connecting said sheets and arranged in a plurality of rows in echelon formation with each tube equidistant from six surrounding tubes, means to pass a fluid through the interior of the tubes, an inlet passage located adjacent to one of the tube sheets and arranged to deliver a second fluid to the spaces between the tubes, tubes being omitted in two non-parallel rows to provide two lanes of substantial width which communicate with the inlet passage and through which the second fluid may flow transversely of the tubes, walls enclosing the tubes and providing a passage through which the second fluid may flow longitudinally of the tubes, and baffles located in said lanes to prevent flow along the lanes and longitudinally of the tubes.
5. A heat exchanger comprising a pair of spaced tube sheets, a group of tubes connecting said sheets and arranged in a plurality of rows in echelon formation, means to pass a fluid through the interior of the tubes, an inlet passage located adjacent to one of the tube sheets and arranged to deliver a second fluid to the spaces between the tubes, tubes being omitted in two non-parallel rows to provide two intersecting lanes of substantial width which communicate with the inlet passage and through which the second fluid may flow transversely of the tubes, walls enclosing the tubes and providing a passage through which the second fluid may flow longitudinally of the tubes, members located at the intersection of the lanes and extending longitudinally of the tubes, and baffles located in the lanes and supported by said members, the baffles being arranged to prevent flow along the lanes and longitudinally of the tubes.
6. A heat exchanger comprising a plurality of parallel tubes arranged in two groups, a partition located between the said groups, means to pass a fluid through the interior of the tubes, a casing surrounding the intermediate portions of the tubes, an inlet passage located adjacent to one end of one group of tubes and arranged to deliver a second fluid to the spaces between the tubes, an outlet passage located adjacent to the corresponding end of the other group of tubes and arranged to receive the second fluid from the spaces between the tubes, a passage located adjacent to the other ends of both groups of tubes to transfer the second fluid from the spaces between the tubes of one group to the spaces between the tubes of the other group, the tubes being for the most part closely spaced but arranged to provide lanes of substantial width which communicate with said passages and through which the second fluid may flow transversely of the tubes, and baffles located in said lanes to prevent flow along the lanes and longitudinally of the tubes.
7. A heat exchanger comprising a plurality of parallel tubes arranged in two groups, a partition located between the said groups, means to pass a fluid through the interior of the tubes of one group in one direction and thence through the interior of the tubes of the other group in the opposite direction, an inlet passage located adjacent to the discharge end of the second group and arranged to deliver a second fluid to the spaces between the tubes, an outlet passage located adjacent to the inlet end of the first group and arranged to receive the second fluid from the spaces between the tubes, a passage located adjacent to the other ends of both groups of tubes to transfer the second fluid from the spaces between the tubes of the second group to the spaces between the tubes of the first group, the tubes being for the most part closely spaced but arranged to provide lanes of substantial width which communicate with said passages and through which the second fluid may flow transversely of the tubes, and baffles located in said lanes to prevent flow along the lanes and longitudinally of the tubes.

MAX H. KUHNER.
